UNITED STATES PATENT OFFICE.

PETER FEEMAN, OF LIMA, OHIO.

IMPROVEMENT IN MACHINES FOR TRIMMING STIRRUPS.

Specification forming part of Letters Patent No. 129,273, dated July 16, 1872.

To all whom it may concern:

Be it known that I, PETER FEEMAN, of Lima, in the county of Allen and State of Ohio, have invented a new and valuable Improvement in Machine for Trimming Stirrups; and I do hereby declare that the following is a full, clear, and exact description of the construction and operation of the same, reference being had to the annexed drawing making a part of this specification, and to the letters and figures of reference marked thereon.

Figure 1 of the drawing is a representation of a vertical sectional view of my invention. Fig. 2 is a horizontal section of the same.

This invention has relation to a machine for rounding and finishing the ends of bent wooden stirrups; and consists in the construction and novel arrangement of a knife, its operating devices, and of a notched bed for holding the stirrup during the finishing process, all as hereinafter more fully described.

Referring to the accompanying drawing, A represents a horizontal bed supporting the working parts of this machine, and notched at *a* to receive the notched cross-bar joining the two ends of a stirrup, so that the longer end of the same may be brought under the knife. The bed should be constructed principally of cast-iron, but the part immediately under the knife may be made of soft metal, so as not to injure the edge thereof when the knife strikes it. B represents a standard, slotted at its up-

per end, and armed with an eccentrically pivoted lever, C, the head D of which works in contact with the upper end of the knife-shank E and causes said knife to be pressed down when the lever-arm is lowered. The knife-shank plays through two slotted bracket-plates, F, projecting from the ends of the back-plate G; and, to prevent any variation in the exactness of its stroke, is preferably made rectangular. A spring, H, is coiled around the shank between the plates F, and has the effect of raising the knife with the upward movement of the lever-arm. I indicates the knife, which is shaped in horizontal section somewhat as the letter U, or of a concavo-convex form. The lower edge is sharpened, and trims the end of the stirrup at once to the proper form when pressed down upon it.

What I claim as my invention, and desire to secure by Letters Patent, is—

The stirrup-trimmer, having the notched bed A, standard B, eccentric lever C D, concavo-convex knife, I, shank E, and spring H, combined substantially as specified.

In testimony that I claim the above I have hereunto subscribed my name in the presence of two witnesses.

PETER FEEMAN.
